UNITED STATES PATENT OFFICE.

JAMES M. LIPPINCOTT, OF OAKLAND, ILLINOIS.

SHELVING.

SPECIFICATION forming part of Letters Patent No. 714,206, dated November 25, 1902.

Application filed February 25, 1901. Serial No. 48,670. (No model.)

To all whom it may concern:

Be it known that I, JAMES M. LIPPINCOTT, a citizen of the United States, residing at Oakland, in the county of Coles and State of Illinois, have made certain new and useful Improvements in Shelving, of which the following is a specification.

My invention is an improvement in that class of shelving in which a shelf-section is movable vertically to a height above the ordinary fixed shelving and then adjusted back over said shelving—such, for instance, as shown in my former patent, No. 641,212, dated January 9, 1900; and the present invention has for an object, among others, to simplify the construction and to provide means whereby to render the apparatus easier to operate, more efficient, and to improve its general appearance; and the invention consists in certain novel constructions and combinations of parts, as will be hereinafter described and claimed.

In the drawings, Figure 1 is a perspective view, partly broken away, of a number of shelving-sections embodying my invention, one of the movable shelving-sections being raised to its uppermost position and another lowered to a point in front of the fixed shelving-section. Fig. 2 is a vertical longitudinal section on about line 2 2 of Fig. 1. Fig. 3 is a vertical longitudinal section on about line 3 3 of Fig. 1. Fig. 4 is an enlarged sectional view of the upper portion of the apparatus with the parts in the position shown in Fig. 2. Fig. 5 is a top plan view of the apparatus, partly broken away. Fig. 6 is a detail perspective view of the top portion of the movable shelving-section. Fig. 7 is a detail sectional view illustrating the construction of the shelving-pulleys with rollers to take the end thrust. Fig. 8 is a detail sectional view illustrating the flanged rail and the grooved pulley. Fig. 9 is a detail perspective view, partly broken away, illustrating the stop-fork for the shelf-blind. Fig. 10 is a detail sectional view illustrating the spring-stop. Fig. 11 is a detail view of the weight.

In carrying out my invention I provide a fixed shelving-section A, and above the same a space to receive the movable shelving-section B. Ordinarily in shelving it is desirable to provide a projecting shelf upon which to

support the goods which are being used in making a sale, and this is usually effected by elevating the base of a fixed shelving-section 55 and providing a projecting shelf permanently fixed at a suitable height; but where the movable shelving-section is employed this projecting fixed shelf forms an obstruction to the downward movement of the shelving-section 60 and necessitates the shortening of such section or requires a greater height of space in which to adjust the shelving-section when not in use than is ordinarily available. For this reason I prefer to provide the fixed shelving-section A with a sliding shelf C, which may be moved in, as shown in Figs. 2 and 3, when not in use or when the movable section is drawn down to the position shown in Fig. 3, or such sliding shelf C may be drawn outward, as shown at the left in Fig. 1, to form a shelf on which to expose the goods whenever desired. I prefer to provide suitable guides at C' for the sliding shelf and to provide at the outer edge of such shelf a rib or 75 bead C², which can abut the outer edge of the shelf adjacent to which the sliding shelf operates, as will be understood from Fig. 1. This shelf C, it will be seen, can be readily adjusted in and out of the way when not in use and 80 can be drawn forward, as shown in Fig. 1, whenever desired. I also prefer to provide one of the shelves of the movable section B with a similar sliding shelf D, which can be operated, as shown in Fig. 1, when the movable section is lowered or when otherwise desired. The movable shelving-section B may 85 preferably be made very light, and where there is a considerable span of shelving I prefer to provide between the ends of the shelves 90 B' of the movable section stay-rods E, which extend between the shelves B', as shown, and support the base-bars E', which extend transversely beneath the shelves and are held by means of nuts E² on the rods E. By preference the rods E pass through slots b', elongated in the direction of length of the shelves B', so the rods can be adjusted toward the ends of the shelves one way or the other to permit their arrangement relatively to any 95 size of packages or boxes that it may be desired to place on the shelf. The stay-rods for the shelves B' are usually arranged in two parts, the lower rod bracing the shelves be-

low and the upper rod the shelves above the shelf adjacent to which the sliding shelf D operates, as will be understood from Figs. 1, 2, and 3.

5 In practice the movable shelving-section B may be made of wood, aluminium, or other suitable material, or when desired both wood and aluminium or other light metal may be employed in the construction of the movable section in such manner as to enable the production of a light strong shelving-section.

The movable shelving-section B is provided at its upper rear corners with rollers F and at its upper front corners with rollers G, the 15 rollers F being arranged to operate in vertical guideways H, which curve rearwardly at their upper ends into the rearwardly-extending guideways H', and the front rollers G operate in the guideways I, which latter extend 20 in advance of the guideways H' and in alignment therewith and curve downwardly at their ends I' to permit the entrance and exit of the rollers G in raising and lowering the shelving-section B. I prefer to arrange the 25 guideways I for the rollers G in horizontal alignment with the guideways H', as thereby I avoid any elevation of the guideways for the front rollers above those for the rear rollers of the movable shelving-section and am 30 thus able to provide an apparatus which will present a better appearance at its upper end. The guideways H, H', and I form tracks for the rollers of the movable shelving-section, and where desired tracks may be provided 35 with a rail or flange J and the pulleys may be be grooved, as shown at j in Fig. 8, to prevent any lateral play of the movable shelving-section; but I prefer to employ the construction shown in Fig. 7, in which the trackways 40 shown at 1 are simply channeled or grooved in one side and the rollers are formed to fit in such channel and include a main roller or wheel 2, which supports the load or weight of the movable shelving-section, and a roller 3 45 to take the end thrust, the axis of the roller 3 being at right angles to that of the roller 2 and such roller 3 being carried in a yoke 4, which is journaled at 5 concentrically with the axis of the roller 2, so the roller 3 may 50 operate universally. The rollers 2 and 3 may be covered with rubber, or the trackway may be covered with rubber, or rubber may be provided on both parts, if desired, to decrease the noise incident to the operation of the 55 apparatus, and the roller or its track, shown in Fig. 8, (or both,) may be made of hard rubber or other suitable material to deaden the noise.

The ropes K, of wire or other material, for raising the shelving-section extend from such 60 shelving-section upwardly over guide-pulleys K', thence downward from guide-pulleys K², and connect with the weights L, which are preferably flanged at L' to slide in grooves L², and so prevent any jamming of the weights 65 in the wells in which they operate. It may be preferred to form the weights in sections

or plates, as shown in Figs. 2 and 11, the plates being slotted at L³, so they can be added and removed as desired to secure a proper counterbalance of the load upon the shelving- 70 section B. By this means from time to time weights may be applied and removed according to the weight of the goods upon the shelving-section. In connecting the cord K with the movable shelving-section it is preferred 75 to provide means for movably connecting the cord with the section, so the stress of the cord will not hinder the horizontal moving of the shelving-section, and this may preferably be accomplished by providing pulleys M' on the 80 cord K, operating in loops or frames M, extending transversely upon the upper end of the movable shelving-section. These frames M operate to strengthen the shelving-section, and I may also form the brackets carrying 85 the rollers F and G to overlap the corners of the shelving-section B and strengthen the same, as will be understood from the construction shown at f at the rear of section B in Fig. 6. The section B is provided with a 90 suitable handhold N, which may be grasped by the hand in raising and lowering the shelving and may be engaged by a pole when necessary.

In connection with the movable shelving-section and the fixed section below the same I prefer to provide a shelf-blind O in the form of a curtain which may be wound upon a spring-roller O', (see the spring at O² in Fig. 5,) and which blind O is provided at its free 100 edge with a slat or other suitable enlargement O³, by which it will be stopped by suitable forks P, carried by the framing, and it is also provided at such edge with a ring or loop Q, which may be automatically engaged by a hook Q' 105 at the upper end of the movable shelving-section and may be caught by a hooked rod when it is desired to lower the blind to cover the lower fixed section of the shelving. This blind O, it will be noticed, is in line with the 110 front edge of the fixed shelving-section A, and it can when the parts are in the position shown in Fig. 2 be drawn down to the base of the section A and be secured by a hook Q², (see Fig. 1,) and thus serve to cover both the 115 fixed and movable shelving-sections, or the blind O may be simply drawn down automatically by the movable shelving-section B to cover the space left vacant by the lowering of said section, as shown at the right in Fig. 1. 120 This blind not only serves to exclude dust and to improve the appearance by hiding the space provided for the shelving-section B, but it may also receive advertisements or be ornamented in any suitable way. In the operation 125 of this blind when the shelving-section is raised and adjusted, as shown at the left in Fig. 1, the blind O will be held in the position shown at the left in said figure by the engagement of its enlarged portion O³ beneath 130 the forks P, as shown in Fig. 4. If now the shelving-section B be drawn forward prepara-

tory to lowering it, its hook Q' will engage the ring Q of the blind O and will draw the said blind down to the position shown at the right in said figure as the movable shelving-

5 section is adjusted to its said position. Manifestly a suitable molding R may be extended across in front of the shelving at the upper end thereof, or such part may be cased in any suitable way.

10 It may be desirable to employ a stop-spring S, such as shown in Fig. 10, for holding the shelving-section from movement in either direction except when forcibly moved past the said spring. This spring is arranged to yield

15 under extra pressure and may be employed to hold the movable shelving-section in its lowermost position or at any suitable height against the action of the counterbalancing-

weight. The movable shelving-section may be found useful for storing away goods when 20 not in season, such as winter goods in summer, and vice versa.

Having thus described my invention, what I claim as new, and desire to secure by Letters Patent, is—

25 In an apparatus substantially as described the combination of the shelves provided with slots elongated in the direction of length of the shelves, stay-rods extended through said slots, and shelf-sustaining portions on the 30 stay-rods beneath the shelves substantially as set forth.

JAMES M. LIPPINCOTT.
